TRANSMISSION SYSTEM.

1,000,077.

Specification of Letters Patent.

Patented Aug. 8, 1911.

Application filed March 3, 1909. Serial No. 481,100.

To all whom it may concern:

Be it known that we, GEORGE C. CUMMINGS, a citizen of Canada, and a subject of King Edward VII, residing at Western Springs, in the county of Cook and State of Illinois, United States of America, and ARCHIBALD WRAY, a citizen of the United States, residing at Chicago, in the county of Cook and State of Illinois, have invented a certain new and useful Improvement in Transmission Systems, of which the following is a full, clear, concise, and exact description, reference being had to the accompanying drawings, forming a part of this specification.

Our invention relates to systems of electrical transmission, and has for its general object the provision of improved means for operating electro-magnetic responsive devices located at a series of receiving stations from a central or transmitting station, the invention finding a most important adaptation to party telephone line practice, certain features of the invention relating particularly to party telephone line practice, where the electro-magnetic responsive devices are employed for signaling purposes, enabling the operator at the transmitting station to signal the party line or receiving stations selectively.

As applied to party telephone lines, our invention has for its further object the provision of means whereby the signal-receiving devices at the various party line or receiving stations may be selected and operated, even though the party line be in use, the equipment being such that the use of the party line for signaling purposes does not interfere with its use for talking purposes.

In carrying out these features of our invention, novel equipment at the transmitting station and at the receiving stations is employed, which renders the system of our invention of especial utility in connection with train dispatchers' lines, for, by means of our invention, the train dispatcher may signal all of the receiving or party line stations, one of said stations, or any plurality of said stations, by mechanism which does not interfere with the conversation that may be going on over the line, and by which the use of the line for talking purposes does not interfere with its use for signaling purposes.

In practicing our invention, we employ a transmission system including a line circuit

leading from a transmitting to a plurality of receiving stations, electro-magnetic responsive apparatus at the receiving stations, one set of instrumentalities distributed among the receiving stations and performing their functions in succession and having partial control of said electro-magnetic responsive apparatus, a second set of instrumentalities distributed among the receiving stations and adapted to complete the control over said responsive apparatus, and means controlled at the transmitting station for causing the operation of one of the said second set of instrumentalities at a selected station to have it coöperate with one of the said first set of instrumentalities located at a selected station to effect the operation of the electro-magnetic responsive apparatus thereat.

In practicing our invention, we preferably employ as a transmission system including a line circuit leading from a transmitting to a plurality of receiving stations, electro-magnetic responsive apparatus at the receiving stations, one set of normally restrained self-operating instrumentalities distributed among the receiving stations and, when released, performing their functions in succession and having partial control of said electro-magnetic responsive apparatus, a second set of instrumentalities distributed among the receiving stations adapted to complete the control over said electro-magnetic responsive apparatus, electro-magnetic mechanism at the receiving stations for releasing said set of self-operating instrumentalities and operating the second set of instrumentalities, and means governed at the transmitting station for effecting the substantially simultaneous operation of said electro-magnetic mechanism to cause one instrumentality of each set at a selected station jointly to effect the operation of the electro-magnetic responsive apparatus thereat.

We will explain our invention more fully by reference to the accompanying drawings, showing the preferred embodiment thereof, which is particularly adapted to railroad practice, though the invention is not to be restricted to the use to which it is put, Figure 1 showing the transmitting station and Figure 2 a plurality of party line stations.

The circuit illustrated is a metallic circuit having two metallic sides 37, 38, though the invention is not to be limited to metallic cir-

cuits. The circuit 37, 38 extends from the party line or receiving stations shown in Fig. 2 to the dispatching, sending or central station shown in Fig. 1.

5 As the invention is embodied in a telephone system in the illustration thereof furnished by the drawings, there is shown at each receiving or party line station, a switch-hook 70 connected with one side of the circuit (the side 37), a receiver 68 having one terminal connected with the other side of the circuit (the side 38), the primary winding 73 and a secondary winding 66 of an induction coil 67, a telephone transmitter 71, and 10 a local battery 72, the entire arrangement being such at each party line station that when the telephone receiver is upon its switch-hook, the said receiver and transmitter are included in open circuits, the 15 switch-hook serving, when relieved of the weight of the receiver, to close the associate local circuit including the transmitter 71, the battery 72 and primary winding 73, and to complete a connection between the sides 20 37, 38 of the party line circuit through the switch-hook 70 and the receiver 68, thereby connecting said receiver in bridge between the sides 37, 38 of the party line. Another bridge conductor is provided at each party 25 line or receiving station, in the embodiment of the invention illustrated, which second bridge conductor, instead of being opened and closed, as is the conductor containing the telephone receiver, is permanently closed, 30 for the purpose of maintaining constant connection of the electro-magnet 50 at each receiving station with the sides 37, 38 of the line circuit. This permanently closed bridge conductor also includes impedance 35 devices 51, 52, so as to prevent the voice-currents that are to be directed to any party line or receiving station from being shunted from the active telephone receiver at such receiving station and for preventing tele- 40 phone currents that are to be impressed upon the line by the telephonic apparatus at a receiving station from being shunted away from the line, which would occur if there were not sufficient impedance in the elements 45 50, 51, 52, inasmuch as the bridge conductor portion containing these elements is in parallel relation with the bridge conductor portion containing the associate telephone receiver 68. The telephone bridge conductor 50 portion contains condensers 65, 69, one upon each side of the included telephone receiver 68, so that direct current that is to be impressed upon the line at the transmitting, sending or central station may be forced 55 through the electro-magnets 50 at the receiving stations for purposes that will appear. A third bridge conductor is provided at each party line or receiving station, which third conductor includes a magneto 60 generator 68', which, when idle, serves to 65

open said third conductor, and, when active, serves to close said third bridge conductor, one terminal of the generator 68' being connected or adapted for circuit connection directly with one side 38 of the line circuit, 70 while the other terminal of the generator 68' is adapted for connection with the other side 37 of the line circuit, through the condenser 65, which is of a capacity that will permit of the current from the generator 68' to pass therethrough to operate a suitable signal appliance 46 at the central or transmitting station, so that the attendant at each party line station may signal the central or transmitting station. The electro-magnet 50 provided at each party line or receiving station has an armature switch including two terminals 54, 55 that constitute the normally separated terminals of a local circuit at each party line station, which includes magnet 56 and a local battery 57.

When the operator or dispatcher at the central or dispatching station desires selectively to signal a receiving or party line station, or a number of such stations, such dispatcher or operator will, by means of suitable apparatus to be described, impress direct current upon the sides 37, 38 of the line circuit, thereby to occasion the simultaneous energization of the electro-magnets 50 at the party line stations, thereby simultaneously to effect closure of the local circuits at the party line or receiving stations, which include the magnets 56, said magnets 56, upon being energized, setting 95 into operation suitable circuit-closing or controlling mechanism at the receiving or party line stations, the circuit-controlling mechanism at the different party line or receiving stations being out of step with each other, 100 so that but one of such mechanisms may at a time perform the function for which such mechanism is provided. Each such circuit-controlling mechanism, each such receiving or party line station, in the embodiment of the invention illustrated, includes a rotating contact arm 59 operated by any suitable mechanism that is released and permitted to become effective when the magnet 56 is energized, as will hereinafter more 115 fully be set forth, and a contact button 60, the distances between the arms 59 and their associate buttons 60 differing at the several party line or receiving stations, so that if said arms 59 are rotated synchronously, but 120 one arm 59 can be in engagement with a contact 60 at a given time, inasmuch as the engagement between the elements 59 and 60 is successively effected at the different stations. As has been made plain, the electro-magnets 50 at all of the party line or receiving stations are simultaneously energized so as to set all of the contact arms 59 in motion through the releasing action of the magnets 56. After the arms 59 have thus been set 125 130

into motion, openings in signal-receiving circuits at the party line stations (which signaling circuits will hereinafter be described) are successively partially closed at the different receiving or party line stations by the engagement of the elements 59, 60. The signal-receiving circuits include each an additional opening that is closed by apparatus governed at the transmitting or central station, which closure is timed to occur with the engagement of the contact elements 59, 60 at the selected station or stations, it being possible in this way to close one signal-receiving circuit of one selected party line station or the signal-receiving circuits of any number of party line or receiving stations, it being possible for the operator at the central station to signal all, one, or any number, of party line stations. In carrying out this feature of the invention, the contacts 54 and 55 at each party line or receiving station, in addition to governing the releasing magnet 56, are also serially related with the contacts 59, 60 in the associated signaling circuit, so that when the electro-magnets 50 are energized during the revolutions of the arms 59, they may, by bringing together the contacts 54 and 55 at all of the party line stations, partially close the signal-receiving circuits at such party line stations, the particular signal-receiving circuit that is completely closed being the one of those whose contacts 59 and 60 are engaged during the engagement of the contacts 54 and 55. While the electro-magnets 50 at the party line stations are employed for the double purpose of effecting the operation of the releasing magnets 56 and partially to control the signal-receiving circuits at the party line stations, it is to be understood that the invention is not to be limited to relays having these two purposes. Suitable apparatus is preferably employed at the central or transmitting station which is designed automatically to time the energizations of the magnets 56, this being preferably so constructed that it may be set not only to select one party line station, but to select any number of party line stations indiscriminately or such central station apparatus may be further set so as to cause the operation of all of the signal receivers at all of the party line stations.

Having thus in a general way described the manner of selecting party line stations for the purpose of causing the operation of the signal receivers thereat, we will now describe the preferred form of signal-receiving outfit employed at each party line or receiving station and the co-operative relation thereof with the electro-magnets 50, and will thereafter describe the preferred form of central station equipment that is adapted to co-operate with the line electro-magnets 50 for the purposes which have herein been set forth.

The signal receiver at each party line is desirably a vibrating bell 63, circuit through which being initially dependent upon the engagement of the contacts 54, 55 at the same time the contacts 59, 60 at the selected station are engaged. Inasmuch as the bell 63 is a vibrating bell whose circuit is intermittently opened and closed, and it being desirable to cause the signal receiver to operate until the attendant at the selected station responds, a holding magnet 61 has a local circuit closed therethrough when the contacts 54, 55, 59 and 60 are in closed circuit relation, the magnet 61 retaining its armature in engagement with the contact 62, whereby a local circuit is established for the magnet 61, which is maintained until the push button 64 is operated by the receiving or party line station attendant to open the circuit of the magnet 61. The vibrating or circuit breaking signal receiver 63 includes the battery 57 and the contact 62, so that the signal receiver, after having once been set into operation, is continued in operation until the contact 62 is excluded from circuit with the bell 63, which exclusion occurs when the push button 64 is operated to deenergize the magnet 61 to separate the armature of the magnet 61 from its contact 62, where the desired opening in the circuit of the signal 63 occurs.

The mechanism including the wiping contact 59 at each of the receiving stations, is a normally restrained self-operating instrumentality, these instrumentalities at the different party line stations serving, when released, to engage the contacts 59, 60 at the different stations, in succession, as has been explained. Any suitable form of self-operating mechanism may be employed to constitute said instrumentality, such, for example, as a spring motor or clock mechanism, which is diagrammatically indicated as having, in addition to the wiping contact 59, a disk 1' mounted upon the second hand-shaft of the clock mechanism and carrying the wiper 59, the mechanism of each clock being normally held at rest by means of the finger arms 5', 6' which have projections engaging the disks 1', 2', the arms 5', 6' moving with the armature 8' about a common center, so that when the armature 8' is attracted, the associate clock mechanism is released, such release occurring simultaneously at all receiving stations, owing to the simultaneous energization of the electro-magnets 50 at all receiving stations.

It will thus be seen that we have provided a transmission system (in the embodiment of the invention illustrated, a signaling or telephone system) including a line circuit (37, 38) leading from a transmitting station to a plurality of receiving stations, electro-magnetic responsive apparatus (the 130

elements 61 and 63, for example) at the receiving stations, one set of normally restrained self-operating instrumentalities (the mechanisms including the wiping contacts 59, for example) distributed among the receiving stations, and, when released, operating in succession and having partial control of said electro-magnetic responsive apparatus, preferably by closing normally 10 separated contacts, a second set of instrumentalities (preferably the additional switching devices 54 and 55) distributed among the receiving stations and adapted to complete the control over said responsive 15 apparatus, and means (preferably the electro-magnets 50) controlled at the transmitting station, for releasing said set of self-operating instrumentalities and causing the operation of a second set of instrumentalities, to cause one of said second set 20 of instrumentalities at a selected station to operate together with one of said first set of instrumentalities, to effect the operation of the electro-magnetic responsive apparatus at the selected station.

The party line terminates at the central or transmitting station indicated in Fig. 1, in the two normally disengaged contacts of the switch governed by the electro-magnet 30 or relay 23, the signal-receiving device 46 at the transmitting station being in bridge of the transmission line 37 and 38, this signal device 46 being operable by current produced by the generators 68' at the different party line stations, the bridge circuit for the device 46 including the condenser 32, so that the direct current which is impressed upon both sides 37, 38 of the transmission line is not shunted. The 35 telephonic apparatus at the central or transmitting station includes a telephone receiver 33 which is preferably permanently in bridge, it being the usual duty of the central station attendant to have the receiver 40 33 constantly at his ear, on which account it is not often necessary to operate the generator 68' when a party line station desires communication with the central or transmitting station, the generators 68' only being used when a calling party line station 45 is not answered when a calling party impresses voice-current upon the telephone line 37, 38. The operator's telephone receiver 33 is in serial relation with the secondary 34 of an induction coil, said receiver and secondary being included in the same bridge between the sides 37 and 38 of the telephone line, said elements 33, 34 being disposed between the condensers 32 and 50 36 included in the same bridge therewith.

The induction coil includes the primary 42 inductively related with the secondary 34, the primary 42 being included in a local circuit with the transmitter 40 and transmitter battery 41, which local circuit is

closed by the switching device 43. A second switching device 44 is also desirably employed, whose contacts, which are normally engaged, constitute terminals of a shunt conductor about the secondary 34 to cut out the opposition to the incoming voice-currents that would otherwise be furnished by the said secondary. The switching devices 43, 44 are desirably simultaneously operable, so that when the central station operator 70 wishes to impress voice-currents upon the line, a simple motion will engage the contacts of the switching device 43, to close the transmitter circuit 40, 41, 42 and to open the shunt about the secondary 34, it 75 being understood that the switching devices 43, 44 are in their respectively normally opened and closed conditions excepting when the central station operator is impressing voice-currents upon the line. The terminals of the limbs 37 and 38 of the telephone line, that are associated with the electro-magnetic switching device 23, are adapted to be engaged by the movable terminals of the battery 24 when the magnet 23 is energized, whereby the battery 24 is bridged between the sides 37, 38 of the telephone line to simultaneously operate the electro-magnets 50 for the purposes which have hitherto been set forth. An impedance device 25 is 90 included in serial relation with the battery 24, a part of said device 25 being included on one side of said battery and the balance of said device on the other side of said battery, the impedance, being high, serving to 95 prevent the shunting of voice-currents impressed upon the telephone line 37, 38, the arrangement of the entire system being such that, owing to the impedance 25, the inclusion of the battery 24 in bridge of the circuit 37, 38 does not interfere with the transmission of voice-currents. The use of the condensers 65, 69, 32 and 36 in the telephone bridges, on the other hand, serve to 100 confine the current from battery 24 to the electro-magnets 50, whereby the telephone line 37, 38 may be used for conversational purposes without any interference from the operation of the selecting apparatus of 105 which the electro-magnets 50 form parts and without any interference from the signaling apparatus, inasmuch as the signaling apparatus at the party line stations is included in local or independent circuits. Impedance devices 51 and 52 are preferably 110 employed also to prevent disturbances that might arise due to the operation of the electro-magnets 50 from reaching the line or telephone sub-station outfits immediately in association therewith.

It being preferred to control the application of the battery 24 to the telephone line by means of the magnet 23, as has been described, said magnet 23 is given an initial energization which releases all of the self- 115 120 125 130

acting instrumentalities of which the wipers 59 form parts, the said magnet 23 being also thereafter energized during the movements of the arms 59, the latter energization of 5 the magnet 23 to occur at just about the time the contacts 59 and 60 of a selected station are in engagement, whereby during the engagement of such contacts 59 and 60 at a selected station, the contacts 54 and 55 10 at said selected station are also closed, whereby the two gaps in the signaling circuit or the circuit of the electro-magnetic responsive device at the selected station are closed, the selected station being the only 15 station at which the two closures at 54, 55, 59 and 60, simultaneously occur, although the contacts 54 and 55 at the remaining party line stations are at the same time engaged, owing to the fact that the elements 20 59 among the different party line stations, are engaged with respect to each other, successively with their contacts 60. It is apparent that not only may one party line or receiving station be thus selected, but that 25 a number of party line or receiving stations may be selected, or that all may be selected, it only being necessary to energize the magnet 23 at the proper times,—those times at which the contacts 59 and 60 of the different 30 stations to be selected are in engagement or are about to be engaged, this result being due to the fact that the instrumentalities of the first set at stations remaining unselected remain free to be operated when a station is 35 in selected condition so that another station or stations may be then selected by the operation of the second set of instrumentalities.

The magnet 23 is initially energized when 40 the switch 22 is closed, the circuit occasioning the initial energization of the magnet 23 being traceable from the battery 17, through the winding of the magnet 23, to the battery 17, by way of two engaged contacts of 45 the switch 22. The successive energization or energizations of the magnet 23 which is or are to occur in order that a party line or receiving station or party line or receiving stations may be selected and signaled, desirably occurs automatically after a suitable instrument has been set and adjusted 50 properly to time the energizations of the magnet 23. To this end, there is employed a wiper 3, which may be understood, for example, to rotate in a clockwise direction, connected with one terminal of the battery 17, and a plurality of contact buttons 4 normally separated from the other terminal of the battery 17, but adapted for connection 55 with said other terminal of the battery 17, through the winding of the magnet 23, when the switches (such as 27, 28, 29) associated with said buttons 4, are closed, each button 4 having one such switch in serial relation 60 therewith.

Switch-actuating plungers 10, 11, 12 are provided for the switches 27, 28, 29, there being as many such plungers as there are buttons 4, included in a set, the drawing illustrating two sets of buttons 4, the wiping arm 3 being adapted to rotate a half revolution each time it is set into motion. The wiping arm 3 is caused to have a fixed ratio of speed with respect to the wiping arms 59 at the party line stations, the elements 3 and 59 desirably moving in synchronism and each desirably moving a half revolution in its full range of operation. There are thus two buttons 4, one in each set of buttons, that are in association with one of the switches 27, 28, 29, the wiper 3 moving over said buttons 4 from its state of rest, which may be with the free end of the wiper completely up or fully down, whereby the battery 17 is successively included in circuit 85 with that button or those buttons 4 that are connected with the actuated switch or switches (27, 28, 29) by the wiper 3, a circuit being established through the magnet 23 each time the wiper 3 encounters a button 4 90 whose associate controlling switch (27, 28 or 29) is closed. As there are as many buttons 4 in each of the two sets as there are party line or receiving stations, and as there are as many switches 27, 28, 29 as there are 95 buttons 4, it is apparent that one or any number or all of the party line stations may have their signal circuits closed, so that the operator at the transmitting station may converse with any receiving or party line 100 station or stations irrespective of the location of such receiving station or stations upon the line, it being further apparent from what has been described, that the central station or transmitting station operator 105 may thus signal various party line stations even though conversation may at the time be in progress. Such a system as this is of especial adaptability in the service of train despatching, as must be very apparent without specific illustration.

As the wiper 3 completes a half revolution, it passes over a contact 21, thereby to include the battery 17 in circuit with the magnet 20, whose armature 19 is thereupon attracted, to close circuit at 18 through another magnet 16, the engagement between the elements 3 and 21 lasting a sufficient length of time to permit the magnet 16 to attract its armature, which is in co-operative 115 relation with a number of detents 13, 14 and 15 associated with the plungers 10, 11 and 12 corresponding to the selected stations, to cause said detents to release those plungers which have been actuated for the purpose 120 of signaling the selected stations, suitable mechanism then coming into play, which need not be described, for restoring said actuated plungers to their normal or idle 125 positions.

The wiper 3 is designed to pass off from the contact 21 before it comes to rest, so that the magnet 16 is again included in open circuit, to permit the detents 13, 14, 15 to 5 assume normal positions, so that when the plungers 10, 11, 12 are selectively depressed to occasion the operation of the signal receivers at selected party line stations, said plungers may be held in their depressed 10 conditions. Thus all the operator at the central or transmitting station is required to do is first to depress the selected plunger or plungers 10, 11 or 12, etc., that correspond to the party line or receiving station or 15 stations to be signaled, whereafter such operator depresses the key 22, primarily to give the magnet 23 its initial energization primarily to operate all of the electro-magnets 50, to set the devices 59 into motion, and 20 thereafter to operate all of the electro-magnets 50 when the element 59 at a selected station is in contact with or is about to come into contact with the associate button 60.

The mechanism employed for operating 25 the wiper 3 at the central or transmitting station is desirably the same as is employed to operate the wipers 59 at the party line or receiving stations, the magnet 9 in Fig. 1 performing the releasing function of the 30 magnet 56 in Fig. 2, the elements 1, 2, 5, 6, 8 in Fig. 1 each performing a function similar to that performed by the elements 1', 2', 5', 6', 8' of Fig. 2.

The metallically continuous bridge conductors that include the electro-magnets 50 and retardation devices 51 and 52 are desirably of very high resistance and retardation, the aggregate retarding effect of the elements 50, 51, 52 having in practice 40 equaled over six hundred thousand ohms to talking current and thirty thousand ohms to sixteen cycle ringing current, and a simple resistance of about fifty-five hundred ohms to direct current. It is obvious that 45 these values may be changed within wide limits without departing from the spirit of our invention. We prefer to employ very high resistance for the metallic bridge conductors containing the elements 50, 51, 52, 50 particularly where there are many stations bridged upon the line, as in railroad work, whereby each individual bridge may not receive current materially in excess of the amount necessary to operate the included 55 relay 50.

The battery 24 should be of high voltage, say one hundred ten volts, to compensate for drop in E. M. F., due to resistance of the line wires, the resistance of each metallically 60 continuous bridge being desirably so great in proportion to the resistance of the line wires, that all of the electro-magnets 50 may receive approximately the same current at the same voltage and operate as nearly as 65 possible simultaneously. By placing the

electro-magnets 50 between the retardation elements 51, 52, such relays are so protected that the signals at the sub-stations or party line stations will not easily be impaired by lightning flashes nor will the relays so 70 readily burn out.

The signal receiver or bell 46 at the transmitting or despatcher's station may have a resistance of twenty-five hundred ohms. The condensers 65 at the receiving or party line stations may each have a capacity of two microfarads so as to insure the passage of strong signaling current from the alternating current generator 68' to the line. The condenser 69 may have a capacity of 80 one microfarad, the condensers 65 and 69 co-operating, as has been stated, to prevent current from the battery 24 from being short circuited from the line relays 50 when party line stations are being selected. 85

While we show a source of current 57 at each of the receiving stations for the purpose of operating the signal receiver thereat, we do not wish to be limited to the location of the sources of current at the receiving stations. 90

While the invention has been shown as applied to railroad practice, it is, of course, understood that the invention is not to be limited to such practice. It is also to be 95 understood that changes may readily be made in the embodiment of the invention illustrated without departing from the spirit of the invention.

Having thus described the invention, there is claimed as new and is desired to secure by Letters Patent the following:—

1. A transmission system including a line circuit leading from a transmitting to a plurality of receiving stations, electro-magnetic responsive apparatus at the receiving stations, one set of instrumentalities distributed among the receiving stations and performing their functions in succession and having partial control of said electro-magnetic responsive apparatus, a second set of instrumentalities distributed among the receiving stations and adapted to further the control over said responsive apparatus, and means controlled at the transmitting station for causing the operation of one of the said second set of instrumentalities at a selected station to have it coöperate with one of the said first set of instrumentalities located at a selected station to take part in operating the electro-magnetic responsive apparatus thereat, there being present means whereby the instrumentalities of the first set at stations remaining unselected remain free to be operated when a station is in selected condition so that another station or stations may be then selected by the operation of the second set of instrumentalities. 115

2. A transmission system including a line circuit leading from a transmitting to a 120

- plurality of receiving stations, electro-magnetic responsive apparatus at the receiving stations, one set of instrumentalities distributed among the receiving stations and 5 performing their functions in succession and having partial control of said electro-magnetic responsive apparatus, a second set of instrumentalities distributed among the receiving stations adapted to further the control 10 over said electro-magnetic responsive apparatus, and apparatus governed at the transmitting station for operating the second set of instrumentalities substantially simultaneously to cause one instrumentality 15 of each set at a selected station jointly to take part in operating the electro-magnetic responsive apparatus thereat, there being present means whereby the instrumentalities of the first set at stations remaining unselected remain free to be operated when a station is in selected condition so that another station or stations may be then selected by the operation of the second set of instrumentalities. 20
- 25 3. A transmission system including a line circuit leading from a transmitting to a plurality of receiving stations, electro-magnetic responsive apparatus at the receiving stations, one set of instrumentalities distributed among the receiving stations and performing their functions in succession and having partial control of said electro-magnetic responsive apparatus, a second set of instrumentalities distributed among the receiving stations adapted to further the control over said electro-magnetic responsive apparatus, and apparatus governed 90 at the transmitting station, for releasing said self-operating instrumentalities and operating the second set of instrumentalities substantially simultaneously to cause one instrumentality of each set at a selected 95 station jointly to take part in operating the electro-magnetic responsive apparatus thereat, there being present means whereby the instrumentalities of the first set at stations remaining unselected remain free to be operated when a station is in selected condition so that another station or stations may be then selected by the operation of the second set of instrumentalities. 100
- 40 4. A transmission system including a line circuit leading from a transmitting to a plurality of receiving stations, electro-magnetic responsive apparatus at the receiving stations, one set of normally restrained self-operating instrumentalities distributed among the receiving stations and, when released, performing their functions in succession and having partial control of said electro-magnetic responsive apparatus, a second set of instrumentalities distributed among the receiving stations adapted to further the control over said electro-magnetic responsive apparatus, electro-magnetic devices at the receiving stations for operating the second set of instrumentalities, and means governed 105 at the transmitting station, for effecting the substantially simultaneous operation of said electro-magnetic devices to cause one instrumentality of each set at a selected station jointly to take part in operating the electro-magnetic responsive apparatus thereat, there being present means whereby the instrumentalities of the first set at stations remaining unselected remain free to be operated when a station is in selected condition so that another station or stations may be then selected by the operation of the second set of instrumentalities. 110
- 45 5. A transmission system including a line circuit leading from a transmitting to a plurality of receiving stations, electro-magnetic responsive apparatus at the receiving stations, one set of normally restrained self-operating instrumentalities distributed among the receiving stations and, when released, performing their functions in succession and having partial control of said electro-magnetic responsive apparatus, a second set of instrumentalities distributed 115 among the receiving stations adapted to further the control over said electro-magnetic responsive apparatus, electro-magnetic mechanism at the receiving stations for releasing said set of self-operating instrumentalities and operating the second set of instrumentalities, and means governed at the transmitting station for effecting the substantially simultaneous operation of said electro-magnetic mechanism to cause one instrumental 120
- 50 65 further the control over said responsive apparatus, and means controlled at the transmitting station for releasing said set of self-operating instrumentalities and causing the operation of one of the said second set of instrumentalities at a selected station to 70 have it coöperate with one of the said first set of instrumentalities located at a selected station to take part in operating the electro-magnetic responsive apparatus thereat, there being present means whereby the instrumentalities of the first set at stations remaining unselected remain free to be operated when a station is in selected condition so that another station or stations may be then selected by the operation of the second set of instrumentalities. 75
- 70 75 80 85 90 95 100 105 110 115 120 125 130

ity of each set at a selected station jointly to take part in operating the electro-magnetic responsive apparatus thereat, there being present means whereby the instrumentalities of the first set at stations remaining unselected remain free to be operated when a station is in selected condition so that another station or stations may be then selected by the operation of the second set of instrumentalities.

7. A transmission system including a line circuit leading from a transmitting to a plurality of receiving stations, electro-magnetic responsive apparatus at the receiving stations, one set of normally restrained instrumentalities distributed among the receiving stations and, when released, performing their functions in succession and having partial control of said electro-magnetic responsive apparatus, a second set of instrumentalities distributed among the receiving stations and adapted to further the control over said responsive apparatus, and means controlled at the transmitting station for releasing said first set of instrumentalities and causing the operation of one of the said second set of instrumentalities at a selected station to have it coöperate with one of the said first set of instrumentalities located at a selected station to take part in operating the electro-magnetic responsive apparatus thereat, there being present means whereby the instrumentalities of the first set at stations remaining unselected remain free to be operated when a station is in selected condition so that another station or stations may be then selected by the operation of the second set of instrumentalities.

8. A transmission system including a line circuit leading from a transmitting to a plurality of receiving stations, electro-magnetic responsive apparatus at the receiving stations, one set of normally restrained instrumentalities distributed among the receiving stations and, when released, performing their functions in succession and having partial control of said electro-magnetic responsive apparatus, a second set of instrumentalities distributed among the receiving stations adapted to further the control over said electro-magnetic responsive apparatus, and apparatus governed at the transmitting station, for releasing said first set of instrumentalities and operating the second set of instrumentalities substantially simultaneously to cause one instrumentality of each set at a selected station jointly to take part in operating the electro-magnetic responsive apparatus thereat, there being present means whereby the instrumentalities of the first set at stations remaining unselected remain free to be operated when a station is in selected condition so that another station or stations may be then selected by the operation of the second set of instrumentalities.

by the operation of the second set of instrumentalities.

9. A transmission system including a line circuit leading from a transmitting to a plurality of receiving stations, electro-magnetic responsive apparatus at the receiving stations, one set of normally restrained instrumentalities distributed among the receiving stations, and, when released, performing their functions in succession and having partial control of said electro-magnetic responsive apparatus, a second set of instrumentalities distributed among the receiving stations adapted to further the control over said electro-magnetic responsive apparatus, electro-magnetic mechanism at the receiving stations for releasing said first set of instrumentalities and operating the second set of instrumentalities, and means governed at the transmitting station for effecting the substantially simultaneous operation of said electro-magnetic mechanism to cause one instrumentality of each set at a selected station jointly to take part in operating the electro-magnetic responsive apparatus thereat, there being present means whereby the instrumentalities of the first set at stations remaining unselected remain free to be operated when a station is in selected condition so that another station or stations may be then selected by the operation of the second set of instrumentalities.

10. A transmission system including a line circuit leading from a transmitting to a plurality of receiving stations, electro-magnetic responsive apparatus at the receiving stations included in independent circuits, one set of instrumentalities distributed among the receiving stations and performing their functions in succession to close one of two breaks normally existing in the circuit of the electro-magnetic responsive apparatus at each receiving station, a second set of instrumentalities distributed among the receiving stations to close the second of the two breaks normally existing in the circuit of the electro-magnetic responsive apparatus at each receiving station, and means controlled at the transmitting station for causing the operation of one of the said second set of instrumentalities at a selected station to have it coöperate with one of the said first set of instrumentalities located at a selected station to take part in effecting the closure of the circuit of the electro-magnetic responsive apparatus thereat, there being present means whereby the instrumentalities of the first set at stations remaining unselected remain free to be operated when a station is in selected condition so that another station or stations may be then selected by the operation of the second set of instrumentalities.

11. A transmission system including a line circuit leading from a transmitting to a plu-

- rality of receiving stations, electro-magnetic responsive apparatus at the receiving stations included in independent circuits, one set of instrumentalities distributed among
- 5 the receiving stations and performing their functions in succession to close one of two breaks normally existing in the circuit of the electro-magnetic responsive apparatus at each receiving station, a second set of in-
10 strumentalities distributed among the receiving stations to close the second of the two breaks normally existing in the circuit of the electro-magnetic responsive apparatus at each receiving station, and apparatus gov-
15 erned at the transmitting station, for operating the second set of instrumentalities substantially simultaneously to cause one instrumentality of each set at a selected station jointly to take part in effecting the clo-
20 sure of the circuit of the electro-magnetic responsive apparatus thereat, there being present means whereby the instrumentalities of the first set at stations remaining unselected remain free to be operated when a station is
25 in selected condition so that another station or stations may be then selected by the operation of the second set of instrumentalities. 85
12. A transmission system including a line circuit leading from a transmitting to a plurality of receiving stations, electro-magnetic responsive apparatus at the receiving stations included in independent circuits, one set of instrumentalities distributed among the receiving stations and performing their
30 functions in succession to close one of two breaks normally existing in the circuit of the electro-magnetic responsive apparatus at each receiving station, a second set of instru-
35 mentalities distributed among the receiving stations to close the second of the two breaks normally existing in the circuit of the electro-magnetic responsive apparatus at each receiving station, electro-magnetic devices at the receiving stations for operating the sec-
40 ond set of instrumentalities, and means gov-
45 erned at the transmitting station, for effecting the substantially simultaneous operation of said electro-magnetic devices to cause one instrumentality of each set at a selected station jointly to take part in effecting the clo-
50 sure of the circuit of the electro-magnetic responsive apparatus thereat, there being present means whereby the instrumentalities of the first set at stations remaining unselected remain free to be operated when a station is
55 in selected condition so that another station or stations may be then selected by the operation of the second set of instrumentalities. 110
13. A transmission system including a line circuit leading from a transmitting to a plurality of receiving stations, electro-magnetic responsive apparatus at the receiving stations included in independent circuits, one set of normally restrained self-operating instrumentalities distributed
60 among the receiving stations and, when released, performing their functions in suc-
65 cection, to close one of two breaks normally existing in the circuit of the electro-magnetic responsive apparatus at each receiv-
70 ing station, a second set of instrumentalities distributed among the receiving stations to close the second of the two breaks normally existing in the circuit of the electro-magnetic responsive apparatus at each receiving station, and means controlled at the transmitting station for releasing said set of self-operating instrumentalities and causing the operation of one of the said second set of instrumentalities at a selected station to have it coöperate with one of the said first set of instrumentalities located at a selected station to take part in effecting the closure of the circuit of the electro-magnetic responsive apparatus thereat, there being 80 present means whereby the instrumentalities of the first set at stations remaining unselected remain free to be operated when a station is in selected condition so that another station or stations may be then selected by 90 the operation of the second set of instrumentalities. 95
14. A transmission system including a line circuit leading from a transmitting to a plurality of receiving stations, electro-magnetic responsive apparatus at the receiving stations included in independent circuits, one set of normally restrained self-operating instrumentalities distributed among the receiving stations and, when released, performing their functions in suc-
100 cection, to close one of two breaks normally existing in the circuit of the electro-magnetic responsive apparatus at each receiving station, a second set of instrumentalities distributed among the receiving stations to close the second of the two breaks normally existing in the circuit of the electro-magnetic responsive apparatus at each receiving station, and apparatus governed at the transmitting station for releasing said set of self-operating instrumentalities and operating the second set of instrumentalities substantially simultaneously to cause one instrumentality of each set at a selected station jointly to take part in effecting the closure of the circuit of the electro-magnetic responsive apparatus thereat there being present means whereby the instrumentalities of the first set at stations remaining unselected remain free to be operated when a station is in selected condition so that another station or stations may be then selected by 105 the operation of the second set of instrumentalities. 110
15. A transmission system including a line circuit leading from a transmitting to a plurality of receiving stations, electro-magnetic responsive apparatus at the receiving stations included in independent 115
- 65

circuits, one set of normally restrained self-operating instrumentalities distributed among the receiving stations and, when released, performing their functions in succession, to close one of two breaks normally existing in the circuit of the electro-magnetic responsive apparatus at each receiving station, a second set of instrumentalities distributed among the receiving stations, to 5 close the second of the two breaks normally existing in the circuit of the electro-magnetic responsive apparatus at each receiving station, electro-magnetic mechanism at the receiving stations for releasing said set of self-operating instrumentalities and operating the second set of instrumentalities, and means governed at the transmitting station, for effecting the substantially simultaneous operation of said electro-magnetic mechanism to cause one instrumentality of each set at a selected station jointly to take part in effecting the closure of the circuit of the electro-magnetic responsive apparatus thereat there being present means whereby the 10 instrumentalities of the first set at stations remaining unselected remain free to be operated when a station is in selected condition so that another station or stations may be then selected by the operation of the second set of instrumentalities.

16. A transmission system including a line circuit leading from a transmitting to a plurality of receiving stations, electro-magnetic responsive apparatus at the receiving stations included in independent circuits, one set of normally restrained instrumentalities distributed among the receiving stations and, when released, performing their functions in succession, to 15 close one of two breaks normally existing in the circuit of the electro-magnetic responsive apparatus at each receiving station, a second set of instrumentalities distributed among the receiving stations, to close the second of the two breaks normally existing in the circuit of the electro-magnetic responsive apparatus at each receiving station, and means controlled at the transmitting station, for releasing said first set of instrumentalities and causing the operation of one of the said second set of instrumentalities at a selected station to have it coöperate with one of the said first set of instrumentalities located at a selected station to take part in effecting the closure of the circuit of the electro-magnetic responsive apparatus thereat there being present means whereby the instrumentalities of the first set at stations remaining unselected remain free to be operated when a station is in selected condition so that another station or stations may be then selected by the operation of the second set of instrumentalities.

17. A transmission system including a line circuit leading from a transmitting to a

plurality of receiving stations, electro-magnetic responsive apparatus at the receiving stations included in independent circuits, one set of normally restrained instrumentalities distributed among the receiving stations and, when released, performing their functions in succession, to close one of two breaks normally existing in the circuit of the electro-magnetic responsive apparatus at each receiving station, a second set of instrumentalities distributed among the receiving stations, to close the second of the two breaks normally existing in the circuit of the electro-magnetic responsive apparatus at each receiving station, and apparatus governed at the transmitting station for releasing said first set of instrumentalities and operating the second set of instrumentalities substantially simultaneously to cause one instrumentality of each set at a selected station jointly to take part in effecting the closure of the circuit of the electro-magnetic responsive apparatus thereat, there being present means whereby the instrumentalities of the first set at stations remaining unselected remain free to be operated when a station is in selected condition so that another station or stations may be then selected by the operation of the second set of instrumentalities.

18. A transmission system including a line circuit leading from a transmitting to a plurality of receiving stations, electro-magnetic responsive apparatus at the receiving stations included in independent circuits, one set of normally restrained instrumentalities distributed among the receiving stations and, when released, performing their functions in succession, to close one of two breaks normally existing in the circuit of the electro-magnetic responsive apparatus at each receiving station, a second set of instrumentalities distributed among the receiving stations, to close the second of the two breaks normally existing in the circuit of the electro-magnetic responsive apparatus at each receiving station, electro-magnetic mechanism at the receiving stations for releasing said set of instrumentalities and operating the second set of instrumentalities, and means governed at the transmitting station, for effecting the substantially simultaneous operation of said electro-magnetic mechanism to cause one instrumentality of each set at a selected station jointly to take part in effecting the closure of the circuit of the electro-magnetic responsive apparatus thereat, there being present means whereby the instrumentalities of the first set at stations remaining unselected remain free to be operated when a station is in selected condition so that another station or stations may be then selected by the operation of the second set of instrumentalities.

19. A transmission system including a

transmission line extending to a transmitting station, a source of current, switching mechanism for including the same in circuit with the transmission line, an electro-magnet 5 governing said switching mechanism whose circuit has one terminal in the form of a wiper, the complement of said terminal being in the form of contact buttons engageable by the wiper, manually operable switching devices governed by the operator, for operatively including a selected contact or contacts in the circuit of said magnet, whereby when said wiper engages a contact or contacts thus operatively included in the 10 circuit of said magnet, said magnet is energized to include the aforesaid source of current in circuit with the line, normally restrained self-operating mechanism for effecting relative movement between the wiper and contacts, electro-magnetic mechanism for releasing said self-operating mechanism, a manually operated switching device for closing circuit through said electro-magnet and said electro-magnetic mechanism for releasing said detents and having for its circuit said wiper and a terminal contact engaged by the wiper when finishing its travel.

20. A transmission system including a transmission line extending to a transmitting station, a source of current, switching mechanism for including the same in circuit with the transmission line, an electro-magnet governing said switching mechanism whose circuit has one terminal in the form of a wiper, the complement to said terminal being in the form of contact buttons engageable by the wiper, manually operable switching devices governed by the operator, for operatively including a selected contact or contacts in the circuit of said magnet, whereby when said wiper engages a contact or contacts thus operatively included in the circuit of said magnet, said magnet is energized to include the aforesaid source of current in circuit with the line, the aforesaid manually operable switching devices being provided 35 with detents for holding the same in actuated positions, and electro-magnetically operated releasing mechanism for releasing said detents and having in its circuit said wiper and a terminal contact engaged by the 40 wiper when finishing its travel.

21. A transmission system including a transmission line extending to a transmitting station, a source of current, switching mechanism for including the same in circuit with the transmission line, an electro-magnet governing said switching mechanism whose circuit has one terminal in the form of a wiper, the complement to said terminal being in the form of contact buttons engageable by the wiper, manually operable switching devices governed by the operator, for operatively including a selected contact or contacts in the circuit of said magnet, whereby when said wiper engages a contact

or contacts thus operatively included in the 65 circuit of said magnet, said magnet is energized to include the aforesaid source of current in circuit with the line, normally restrained self-operating mechanism for effecting relative movement between the wiper and contacts, electro-magnetic mechanism for releasing said self-operating mechanism, a manually operated switching device for closing circuit through said electro-magnet and said electro-magnetic mechanism, the aforesaid manually operable switching devices being provided with detents for holding the same in actuated positions, and electro-magnetically operated releasing mechanism for releasing said detents and having for its circuit 70 said wiper and a terminal contact engaged by the wiper when finishing its travel.

22. A signaling system including a line circuit leading from a transmitting to a plurality of receiving stations, signal receiving apparatus at the receiving stations, one set of instrumentalities distributed among the receiving stations and performing their functions in succession and having partial control of said signal receiving apparatus, a 85 second set of instrumentalities distributed among the receiving stations and adapted to further the control over said responsive apparatus, and means controlled at the transmitting station for causing the operation of 90 one of the said second set of instrumentalities at a selected station to have it coöperate with one of the said first set of instrumentalities located at a selected station to take part in operating the signal-receiving apparatus thereat, there being present means whereby the instrumentalities of the first set at stations remaining unselected remain free to be operated when a station is in selected condition so that another station or stations 95 may be then selected by the operation of the second set of instrumentalities.

23. A signaling system including a line circuit leading from a transmitting to a plurality of receiving stations, signal receiving 100 apparatus at the receiving stations, one set of instrumentalities distributed among the receiving stations and performing their functions in succession and having partial control of said signal receiving apparatus, a 110 second set of instrumentalities distributed among the receiving stations adapted to further the control over said signal receiving apparatus, and apparatus governed at the transmitting station for operating the second set of instrumentalities substantially simultaneously to cause one instrumentality of each set at a selected station jointly to take part in operating the signal receiving apparatus thereat, there being present means whereby the instrumentalities of the first set at stations remaining unselected remain free to be operated when a station is in selected 120 condition.

condition so that another station or stations may be then selected by the operation of the second set of instrumentalities.

24. A signaling system including a line circuit leading from a transmitting to a plurality of receiving stations, signal receiving apparatus at the receiving stations, one set of instrumentalities distributed among the receiving stations and performing their functions in succession and having partial control of said signal-receiving apparatus, a second set of instrumentalities distributed among the receiving stations adapted to further the control over said signal-receiving apparatus, electro-magnetic devices at the receiving stations for operating the second set of instrumentalities, and means governed at the transmitting station, for effecting the substantially simultaneous operation of said signal-receiving devices to cause one instrumentality of each set at a selected station jointly to take part in operating the signal-receiving apparatus thereat, there being present means whereby the instrumentalities of the first set at stations remaining unselected remain free to be operated when a station is in selected condition so that another station or stations may be then selected by the operation of the second set of instrumentalities.
25. A signaling system including a line circuit leading from a transmitting to a plurality of receiving stations signal-receiving apparatus at the receiving stations, one set of normally restrained self-operating instrumentalities distributed among the receiving stations and, when released, performing their functions in succession and having partial control of said signal-receiving apparatus, a second set of instrumentalities distributed among the receiving stations and adapted to further the control over said signal-receiving apparatus, and means controlled at the transmitting station for releasing said set of self-operating instrumentalities and causing the operation of one of the said second set of instrumentalities at a selected station to have it coöperate with one of the said first set of instrumentalities located at a selected station to take part in operating the signal-receiving apparatus thereat, there being present means whereby the instrumentalities of the first set at stations remaining unselected remain free to be operated when a station is in selected condition so that another station or stations may be then selected by the operation of the second set of instrumentalities.
26. A signaling system including a line circuit leading from a transmitting to a plurality of receiving stations, signal-receiving apparatus at the receiving stations, one set of normally restrained self-operating instrumentalities distributed among the receiving stations and, when released, performing their functions in succession and having

partial control of said signal-receiving apparatus, a second set of instrumentalities distributed among the receiving stations adapted to further the control over said signal-receiving apparatus, and apparatus governed at the transmitting station, for releasing said self-operating instrumentalities and operating the second set of instrumentalities substantially simultaneously to cause one instrumentality of each set at a selected station jointly to take part in operating the signal-receiving apparatus thereat, there being present means whereby the instrumentalities of the first set at stations remaining unselected remain free to be operated when a station is in selected condition so that another station or stations may be then selected by the operation of the second set of instrumentalities.

27. A signaling system including a line circuit leading from a transmitting to a plurality of receiving stations, signal-receiving apparatus at the receiving stations, one set of normally restrained self-operating instrumentalities distributed among the receiving stations adapted to further the control over said signal-receiving apparatus, a second set of instrumentalities distributed among the receiving stations adapted to further the control over said signal-receiving apparatus, electro-magnetic mechanism at the receiving stations for releasing said set of self-operating instrumentalities and operating the second set of instrumentalities and means governed at the transmitting station for effecting the substantially simultaneous operation of said electro-magnetic mechanism to cause one instrumentality of each set at a selected station jointly to take part in operating the signal-receiving apparatus thereat, there being present means whereby the instrumentalities of the first set at stations remaining unselected remain free to be operated when a station is in selected condition so that another station or stations may be then selected by the operation of the second set of instrumentalities.

28. A signaling system including a line circuit leading from a transmitting to a plurality of receiving stations, signal-receiving apparatus at the receiving stations, one set of normally restrained instrumentalities distributed among the receiving stations and, when released, performing their functions in succession and having partial control of said signal-receiving apparatus, a second set of instrumentalities distributed among the receiving stations and adapted to further the control over said signal-receiving apparatus, and means controlled at the transmitting station for releasing said first set of instrumentalities and causing the operation of one of the said second set of in-

strumentalities at a selected station to have it coöperate with one of the said first set of instrumentalities located at a selected station to take part in operating the signal-receiving apparatus thereat, there being present means whereby the instrumentalities of the first set at stations remaining unselected remain free to be operated when a station is in selected condition so that another station or stations may be then selected by the operation of the second set of instrumentalities.

29. A signaling system including a line circuit leading from a transmitting to a plurality of receiving stations, signal-receiving apparatus at the receiving stations, one set of normally restrained instrumentalities distributed among the receiving stations and, when released, performing their functions in succession and having partial control of said signal-receiving apparatus, a second set of instrumentalities distributed among the receiving stations adapted to further the control over said signal-receiving apparatus, and apparatus governed at the transmitting station, for releasing said first set of instrumentalities and operating the second set of instrumentalities substantially simultaneously to cause one instrumentality of each set at a selected station jointly to take part in operating the signal-receiving apparatus thereat, there being present means whereby the instrumentalities of the first set at stations remaining unselected remain free to be operated when a station is in selected condition so that another station or stations may be then selected by the operation of the second set of instrumentalities.

30. A signaling system including a line circuit leading from a transmitting to a plurality of receiving stations, signal-receiving apparatus at the receiving stations, one set of normally restrained instrumentalities distributed among the receiving stations, and, when released, performing their functions in succession and having partial control of said signal-receiving apparatus, a second set of instrumentalities distributed among the receiving stations adapted to further the control over said signal-receiving apparatus, electro-magnetic mechanism at the receiving stations for releasing said first set of instrumentalities and operating the second set of instrumentalities, and means governed at the transmitting station for effecting the substantially simultaneous operation of said electro-magnetic mechanism to cause one instrumentality of each set at a selected station jointly to take part in operating the signal-receiving apparatus thereat, there being present means whereby the instrumentalities of the first set at stations remaining unselected remain free to be operated when a station is in selected condition so that another station or stations may be

then selected by the operation of the second set of instrumentalities.

31. A signaling system including a line circuit leading from a transmitting to a plurality of receiving stations, signal-receiving apparatus at the receiving stations included in independent circuits, one set of instrumentalities distributed among the receiving stations and performing their functions in succession to close one of two breaks normally existing in the circuit of the signal-receiving apparatus at each receiving station, a second set of instrumentalities distributed among the receiving stations to close the second of the two breaks normally existing in the circuit of the signal-receiving apparatus at each receiving station, and means controlled at the transmitting station for causing the operation of one of the said second set of instrumentalities at a selected station to have it coöperate with one of the said first set of instrumentalities located at a selected station to take part in effecting the closure of the circuit of the signal-receiving apparatus thereat, there being present means whereby the instrumentalities of the first set at stations remaining unselected remain free to be operated when a station is in selected condition so that another station or stations may be then selected by the operation of the second set of instrumentalities.

32. A signaling system including a line circuit leading from a transmitting to a plurality of receiving stations, signal-receiving apparatus at the receiving stations included in independent circuits, one set of instrumentalities distributed among the receiving stations and performing their functions in succession to close one of two breaks normally existing in the circuit of the signal-receiving apparatus at each receiving station, a second set of instrumentalities distributed among the receiving stations to close the second of the two breaks normally existing in the circuit of the signal-receiving apparatus at each receiving station, and apparatus governed at the transmitting station, for operating the second set of instrumentalities substantially simultaneously to cause one instrumentality of each set at a selected station jointly to take part in effecting the closure of the circuit of the signal-receiving apparatus thereat, there being present means whereby the instrumentalities of the first set at stations remaining unselected remain free to be operated when a station is in selected condition so that another station or stations may be then selected by the operation of the second set of instrumentalities.

33. A signaling system including a line circuit leading from a transmitting to a plurality of receiving stations, signal-receiving apparatus at the receiving stations included in independent circuits, one set of instrumentalities distributed among the re-

ceiving stations and performing their functions in succession to close one of two breaks normally existing in the circuit of the signal-receiving apparatus at each 5 receiving station, a second set of instrumentalities distributed among the receiving stations to close the second of the two breaks normally existing in the circuit of the signal-receiving apparatus at 10 each receiving station, electro-magnetic devices at the receiving stations for operating the second set of instrumentalities, and means governed at the transmitting station, for effecting the substantially simultaneous 15 operation of said electro-magnetic devices to cause one instrumentality of each set at a selected station jointly to take part in effecting the closure of the circuit of the signal-receiving apparatus thereat, there being 20 present means whereby the instrumentalities of the first set at stations remaining unselected remain free to be operated when a station is in selected condition so that another station or stations may be then selected 25 by the operation of the second set of instrumentalities.

34. A signaling system including a line circuit leading from a transmitting to a plurality of receiving stations, signal-receiving 30 apparatus at the receiving stations included in independent circuits, one set of normally restrained self-operating instrumentalities distributed among the receiving stations and, when released, performing their functions in succession, to close one of two breaks 35 normally existing in the circuit of the signal-receiving apparatus at each receiving station, a second set of instrumentalities distributed among the receiving stations to 40 close the second of the two breaks normally existing in the circuit of the signal-receiving apparatus at each receiving station, and means controlled at the transmitting station for releasing said set of self-operating 45 instrumentalities and causing the operation of one of the said second set of instrumentalities at a selected station to have it coöperate with one of the said first set of instrumentalities located at a selected station to 50 take part in effecting the closure of the circuit of the signal-receiving apparatus thereat, there being present means whereby the instrumentalities of the first set at stations remaining unselected remain free to be operated 55 when a station is in selected condition so that another station or stations may be then selected by the operation of the second set of instrumentalities.

35. A signaling system including a line 60 circuit leading from a transmitting to a plurality of receiving stations, signal-receiving apparatus at the receiving stations included in independent circuits, one set of normally restrained self-operating instrumentalities distributed among the receiving

stations and, when released, performing their functions in succession, to close one of two breaks normally existing in the circuit of the signal-receiving apparatus at each receiving station, a second set of instrumentalities distributed among the receiving stations to close the second of the two breaks normally existing in the circuit of the signal-receiving apparatus at each receiving station, and apparatus governed at 70 the transmitting station for releasing said set of self-operating instrumentalities and operating the second set of instrumentalities substantially simultaneously to cause one instrumentality of each set at a selected station jointly to take part in effecting the closure of the circuit of the signal-receiving apparatus thereat, there being present means whereby the instrumentalities of the first set at stations remaining unselected remain free to be operated when a station is in selected condition so that another station or stations may be then selected by the operation of the second set of instrumentalities. 80

36. A signaling system including a line circuit leading from a transmitting to a plurality of receiving stations, signal-receiving apparatus at the receiving stations included in independent circuits, one set of normally restrained self-operating instrumentalities distributed among the receiving stations and, when released, performing their functions in succession, to close one of two breaks normally existing in the circuit of the signal-receiving apparatus at each receiving station, a second set of instrumentalities distributed among the receiving stations, to close the second set of the two breaks normally existing in the circuit of the signal-receiving apparatus at each receiving station, electro-magnetic mechanism at the receiving stations for releasing said set of self-operating instrumentalities and operating the second set of instrumentalities, and means governed at the transmitting station, for effecting the substantially simultaneous operation of said electro-magnetic mechanism to cause one instrumentality of each set at a selected station jointly to take part in effecting the closure of the circuit of the signal-receiving apparatus thereat, there being present means whereby the instrumentalities of the first set at stations remaining unselected remain free to be operated when a station is in selected condition so that another station or stations may be then selected by the operation of the second set of instrumentalities. 90

37. A signaling system including a line circuit leading from a transmitting to a plurality of receiving stations, signal-receiving apparatus at the receiving stations included in independent circuits, one set of normally restrained instrumentalities distributed among the receiving stations and, 100

- when released, performing their functions in succession, to close one of two breaks normally existing in the circuit of the signal-receiving apparatus at each receiving station, a second set of instrumentalities distributed among the receiving stations, to close the second of the two breaks normally existing in the circuit of the signal-receiving apparatus at each receiving station, and
- 5 means controlled at the transmitting station, for releasing said first set of instrumentalities and causing the operation of one of the said second set of instrumentalities at a selected station to have it coöperate with one
- 10 of the said first set of instrumentalities located at a selected station to take part in effecting the closure of the circuit of the signal-receiving apparatus thereat, there being present means whereby the instrumentalities of the first set at stations remaining unselected remain free to be operated when a station is in selected condition so that another station or stations may be then selected by the operation of the second set of instrumentalities.
- 15 38. A signaling system including a line circuit leading from a transmitting to a plurality of receiving stations, signal-receiving apparatus at the receiving stations included in independent circuits, one set of normally restrained instrumentalities distributed among the receiving stations and, when released, performing their functions in succession, to close one of two breaks
- 20 normally existing in the circuit of the signal-receiving apparatus at each receiving station, a second set of instrumentalities distributed among the receiving stations, to close the second of the two breaks normally existing in the circuit of the signal-receiving apparatus at each receiving station, and apparatus governed at the transmitting station for releasing said first set of instrumentalities and operating the second set of instrumentalities substantially simultaneously to cause one instrumentality of each set at a selected station jointly to take part in effecting the closure of the circuit of the signal-receiving apparatus thereat, there being present means whereby the instrumentalities of the first set at stations remaining unselected remain free to be operated when a station is in selected condition so that another station or stations may be then selected by the operation of the second set of instrumentalities.
- 25 39. A signaling system including a line circuit leading from a transmitting to a plurality of receiving stations, signal-receiving apparatus at the receiving stations included in independent circuits, one set of normally restrained instrumentalities distributed among the receiving stations, and, when released, performing their functions in succession, to close one of two breaks nor-
- mally existing in the circuit of the signal-receiving apparatus at each receiving station, a second set of instrumentalities distributed among the receiving stations, to close the second of the two breaks normally existing
- 30 in the circuit of the signal-receiving apparatus at each receiving station, electro-magnetic mechanism at the receiving stations for releasing said set of instrumentalities and operating the second set of instrumentalities,
- 35 and means governed at the transmitting station, for effecting the substantially simultaneous operation of said electro-magnetic mechanism to cause one instrumentality of each set at a selected station jointly to take part in effecting the closure of the circuit of the signal-receiving apparatus thereat, there being present means whereby the instrumentalities of the first set at stations remaining unselected remain free to be operated when a station is in selected condition so that another station or stations may be then selected by the operation of the second set of instrumentalities.
- 40 40. A party line telephone system including a line circuit leading from a transmitting to a plurality of receiving stations, each having telephonic apparatus in a telephonically continuous but metallically discontinuous bridge between the sides of the line circuit, signal-receiving apparatus at the receiving stations, one set of instrumentalities distributed among the receiving stations and performing their functions in succession and having partial control of said signal-receiving apparatus, a second set of instrumentalities distributed among the receiving stations and adapted to further the control over said signal-receiving apparatus, electro-magnets at the receiving stations in
- 45 metallically continuous bridges between the sides of the party line, and switching mechanism at the transmitting station for operating said electro-magnets to cause the operation of one of the said second set of instrumentalities at a selected station to have it co-operate with one of the said first set of instrumentalities located at a selected station to take part in operating the signal-receiving apparatus thereat, there being present means whereby the instrumentalities of the first set at stations remaining unselected remain free to be operated when a station is in selected condition so that another station or stations may be then selected by the operation of the second set of instrumentalities.
- 50 41. A party line telephone system including a line circuit leading from a transmitting to a plurality of receiving stations, each having telephonic apparatus in a telephonically continuous but metallically discontinuous bridge between the sides of the line circuit, signal-receiving apparatus at the receiving stations, one set of instrumentalities distributed among the receiving stations and

performing their functions in succession and having partial control of said signal-receiving apparatus, a second set of instrumentalities distributed among the receiving stations and having government exercised from the transmitting station that is independent of government exercised by the first set of instrumentalities and adapted to further the control over said signal-receiving apparatus, electro-magnets at the receiving stations in metallically continuous bridges between the sides of the party line, and switching mechanism at the transmitting station for operating said electro-magnets to operate the second set of instrumentalities substantially simultaneously to cause one instrumentality of each set at a selected station jointly to take part in operating the signal-receiving apparatus thereat.

42. A party line telephone system including a line circuit leading from a transmitting to a plurality of receiving stations, each having telephonic apparatus in a telephonically continuous but metallically discontinuous bridge between the sides of the line circuit, signal-receiving apparatus at the receiving stations, one set of instrumentalities distributed among the receiving stations and performing their functions in succession and having partial control of said signal-receiving apparatus, a second set of instrumentalities distributed among the receiving stations and having government exercised from the transmitting station that is independent of government exercised by the first set of instrumentalities and adapted to further the control over said signal-receiving apparatus, electro-magnetic devices at the receiving stations for operating the second set of instrumentalities, electro-magnets at the receiving stations in metallically continuous bridges between the sides of the party line, and switching mechanism at the transmitting station for operating said electro-magnets to effect the substantially simultaneous operation of said electro-magnetic devices to cause one instrumentality of each set at a selected station jointly to take part in operating the signal-receiving apparatus thereat.

43. A party line telephone system including line circuit leading from a transmitting to a plurality of receiving stations, each having telephonic apparatus in a telephonically continuous but metallically discontinuous bridge between the sides of the line circuit, signal-receiving apparatus at the receiving stations, one set of normally restrained self-operating instrumentalities distributed among the receiving stations and, when released, performing their functions in succession and having partial control of said signal-receiving apparatus, a second set of instrumentalities distributed among the receiving stations and having government exercised from the transmitting station that is independent of government exercised by

ment exercised from the transmitting station that is independent of government exercised by the first set of instrumentalities and adapted to further the control over said responsive apparatus, electro-magnets at the receiving stations in metallically continuous bridges between the sides of the party line, and switching mechanism at the transmitting station for operating said electro-magnets to release said set of self-operating instrumentalities and causing the operation of one of the said second set of instrumentalities at a selected station to have it coöperate with one of the said first set of instrumentalities located at a selected station to take part in operating the signal-receiving apparatus thereat.

44. A party line telephone system including a line circuit leading from a transmitting to a plurality of receiving stations, each having telephonic apparatus in a telephonically continuous but metallically discontinuous bridge between the sides of the line circuit, signal-receiving apparatus at the receiving stations, one set of normally restrained self-operating instrumentalities distributed among the receiving stations and, when released, performing their functions in succession and having partial control of said signal-receiving apparatus, a second set of instrumentalities distributed among the receiving stations and having government exercised from the transmitting station that is independent of government exercised by the first set of instrumentalities adapted to further the control over said signal-receiving apparatus, electro-magnets at the receiving stations in metallically continuous bridges between the sides of the party line, and switching mechanism at the transmitting station for operating said electro-magnets to release said self-operating instrumentalities and operating the second set of instrumentalities substantially simultaneously to cause one instrumentality of each set at a selected station jointly to take part in operating the signal-receiving apparatus thereat.

45. A party line telephone system including a line circuit leading from a transmitting to a plurality of receiving stations, each having telephonic apparatus in a telephonically continuous but metallically discontinuous bridge between the sides of the line circuit, signal-receiving apparatus at the receiving stations, one set of normally restrained self-operating instrumentalities distributed among the receiving stations and, when released, performing their functions in succession and having partial control of said signal-receiving apparatus, a second set of instrumentalities distributed among the receiving stations and having government exercised from the transmitting station that is independent of government exercised by

the first set of instrumentalities and adapted to further the control over said signal-receiving apparatus, electro-magnetic mechanism at the receiving stations for releasing 5 said set of self-operating instrumentalities and operating the second set of instrumentalities, electro-magnets at the receiving stations in metallically continuous bridges between the sides of the party line, and switching 10 mechanism at the transmitting station for operating said electro-magnets to effect the substantially simultaneous operation of said electro-magnetic mechanism to cause one instrumentality of each set at a selected 15 station jointly to take part in operating the signal-receiving apparatus thereat.

46. A party line telephone system including a line circuit leading from a transmitting to a plurality of receiving stations, each 20 having telephonic apparatus in a telephonically continuous but metallically discontinuous bridge between the sides of the line circuit, signal-receiving apparatus at the receiving stations, one set of normally restrained instrumentalities distributed among 25 the receiving stations and, when released, performing their functions in succession and having partial control of said signal-receiving apparatus, a second set of instrumentalities distributed among the receiving stations and having government exercised from 30 the transmitting station that is independent of government exercised by the first set of instrumentalities and adapted to further 35 the control over said responsive apparatus, electro-magnets at the receiving stations in metallically continuous bridges between the sides of the party line, and switching mechanism at the transmitting station for operating 40 said electro-magnets to release said set of instrumentalities and causing the operation of one of the said second set of instrumentalities at a selected station to have it cooperate with one of the said first set of instrumentalities located at a selected station 45 to take part in operating the signal-receiving apparatus thereat.

47. A party line telephone system including a line circuit leading from a transmitting to a plurality of receiving stations, each having telephonic apparatus in a telephonically continuous but metallically discontinuous bridge between the sides of the line circuit, signal-receiving apparatus at the receiving stations, one set of normally restrained instrumentalities distributed among the receiving stations and, when released, performing their functions in succession and having partial control of said signal-receiving apparatus, a second set of instrumentalities distributed among the receiving stations and having government exercised from the transmitting station that is independent of government exercised by the first set of instrumentalities and adapted to further the

control over said signal-receiving apparatus, electro-magnets at the receiving stations in metallically continuous bridges between the sides of the party line, and switching mechanism at the transmitting station for operating 70 said electro-magnets to release said instrumentalities and operating the second set of instrumentalities substantially simultaneously to cause one instrumentality of each set at a selected station jointly to take part 75 in operating the signal-receiving apparatus thereat.

48. A party line telephone system including a line circuit leading from a transmitting to a plurality of receiving stations, each having telephonic apparatus in a telephonically continuous but metallically discontinuous bridge between the sides of the line circuit, signal-receiving apparatus at the receiving stations, one set of normally restrained instrumentalities distributed among the receiving stations and, when released, performing their functions in succession and having partial control of said signal-receiving apparatus, a second set of instrumentalities distributed among the receiving stations and having government exercised from the transmitting station that is independent of government exercised by the first set of instrumentalities and adapted to further the control over said signal-receiving apparatus, electro-magnetic mechanism at the receiving stations for releasing said set of instrumentalities and operating the second set of instrumentalities, electro-magnets at the receiving stations in metallically continuous bridges between the sides of the party line, and switching mechanism at the transmitting station for operating said electro-magnets to effect the substantially simultaneous operation of said electro-magnetic mechanism to cause one instrumentality of each set at a selected station jointly to take part in operating the signal-receiving apparatus thereat.

49. A party line telephone system including a line circuit leading from a transmitting to a plurality of receiving stations, each having telephonic apparatus in a telephonically continuous but metallically discontinuous bridge between the sides of the line circuit, signal-receiving apparatus at the receiving stations included in independent circuits, one set of instrumentalities distributed among the receiving stations and performing their functions in succession to close one of two breaks normally existing in the circuit of the signal-receiving apparatus at each receiving station, a second set of instrumentalities distributed among the receiving stations and having government exercised from the transmitting station that is independent of government exercised by the first set of instrumentalities, to close the second of the two breaks normally existing 130

in the circuit of the signal-receiving apparatus at each receiving station, electro-magnets at the receiving stations in metallically continuous bridges between the sides of the 5 party line, and switching mechanism at the transmitting station for operating said electro-magnets to cause the operation of one of the said second set of instrumentalities at a selected station to have it coöperate with one 10 of the said first set of instrumentalities located at a selected station to take part in effecting the closure of the circuit of the signal-receiving apparatus thereat.

50. A party line telephone system including a line circuit leading from a transmitting to a plurality of receiving stations, each having telephonic apparatus in telephonically continuous but metallically discontinuous bridge between the sides of the 15 line circuit, signal-receiving apparatus at the receiving stations included in independent circuits, one set of instrumentalities distributed among the receiving stations and performing their functions in succession to 20 close one of two breaks normally existing in the circuit of the signal-receiving apparatus at each receiving station, a second set of instrumentalities distributed among the receiving stations and having government ex- 25 cised from the transmitting station that is independent of government exercised by the first set of instrumentalities, to close the second of the two breaks normally existing in the circuit of the signal-receiving appa- 30 ratus at each receiving station, electro-magnets at the receiving stations in metallically continuous bridges between the sides of the party line, and switching mechanism at the transmitting station for operating said 35 electro-magnets to operate the second set of instrumentalities substantially simultaneously to cause one instrumentality of each set at a selected station jointly to take part in effecting the closure of the circuit of the 40 signal-receiving apparatus thereat.

51. A party line telephone system including a line circuit leading from a transmitting to a plurality of receiving stations, each having telephonic apparatus in a telephonically continuous but metallically discontinuous bridge between the sides of the line circuit, signal-receiving apparatus at the receiving stations included in independent circuits, one set of instrumentalities distributed among the receiving stations and performing their functions in succession to 55 close one of two breaks normally existing in the circuit of the signal-receiving apparatus at each receiving station, a second set of instrumentalities distributed among the receiving stations and having government exercised from the transmitting station that is independent of government ex- 60 cised by the first set of instrumentalities, to close the second of the two breaks nor- 65

mally existing in the circuit of the signal-receiving apparatus at each receiving station, electro-magnetic devices at the receiving stations for operating the second set of instrumentalities, electro-magnets at the receiving stations in metallically continuous bridges between the sides of the party line, and switching mechanism at the transmitting station for operating said electro-magnets to effect the substantially simultaneous 70 operation of said electro-magnetic devices to cause one instrumentality of each set at a selected station jointly to take part in effecting the closure of the circuit of the signal-receiving apparatus thereat. 80

52. A party line telephone system including a line circuit leading from a transmitting to a plurality of receiving stations, each having telephonic apparatus in a telephonically continuous but metallically discontinuous bridge between the sides of the line circuit, signal-receiving apparatus at the receiving stations included in independent circuits, one set of normally restrained self-operating instrumentalities distributed among the receiving stations and, when released, performing their functions in succession, to close one of two breaks normally existing in the circuit of the signal-receiving apparatus at each receiving station, a second set of instrumentalities distributed among the receiving stations and having government exercised from the transmitting station that is independent of government 90 exercised by the first set of instrumentalities, to close the second of the two breaks normally existing in the circuit of the signal-receiving apparatus at each receiving station, a second set of instrumentalities distributed among the receiving stations and having government exercised from the transmitting station that is independent of government 95 exercised by the first set of instrumentalities, to close the second of the two breaks normally existing in the circuit of the signal-receiving apparatus at each receiving station, electro-magnets at the receiving stations in metallically continuous bridges between the sides of the party line, and switching mechanism at the transmitting station for operating said electro-magnets to release said set of self-operating instrumentalities and causing the operation of one 100 of the said second set of instrumentalities at a selected station to have it coöperate with one of the said first set of instrumentalities located at a selected station to take part in effecting the closure of the circuit of the signal-receiving apparatus thereat. 110

53. A party line telephone system including a line circuit leading from a transmitting to a plurality of receiving stations, each having telephonic apparatus in a telephonically continuous but metallically discontinuous bridge between the sides of the line circuit, signal-receiving apparatus at the receiving stations included in independent circuits, one set of normally restrained self-operating instrumentalities distributed among the receiving stations and, when released, performing their functions in succession, to close one of two breaks normally existing in 120 the circuit of the signal-receiving apparatus 125

- at each receiving station, a second set of instrumentalities distributed among the receiving stations and having government exercised from the transmitting station that is independent of government exercised by the first set of instrumentalities, to close the second of the two breaks normally existing in the circuit of the signal-receiving apparatus at each receiving station, electro-magnetic mechanism at the receiving stations in metallically continuous bridges between the sides of the party line, and switching mechanism at the transmitting station for operating said electro-magnets to release said set of self-operating instrumentalities and operating the second set of instrumentalities substantially simultaneously to cause one instrumentality of each set at a selected station jointly to take part in effecting the closure of the circuit of the signal-receiving apparatus thereat. 54. A party line telephone system including a line circuit leading from a transmitting to a plurality of receiving stations, each having telephonic apparatus in a telephonically continuous but metallically discontinuous bridge between the sides of the line circuit, signal-receiving apparatus at the receiving stations included in independent circuits, one set of normally restrained self-operating instrumentalities distributed among the receiving stations and, when released, performing their functions in succession, to close one of two breaks normally existing in the circuit of the signal-receiving apparatus at each receiving station, a second set of instrumentalities distributed among the receiving stations, and having government exercised from the transmitting station that is independent of government exercised by the first set of instrumentalities, to close the second of the two breaks normally existing in the circuit of the signal-receiving apparatus at each receiving station, electro-magnetic mechanism at the receiving stations for releasing said set of self-operating instrumentalities and operating the second set of instrumentalities, electro-magnets at the receiving stations in metallically continuous bridges between the sides of the party line, and switching mechanism at the transmitting station for operating said electro-magnets to effect the substantially simultaneous operation of said electro-magnetic mechanism to cause one instrumentality of each set at a selected station jointly to take part in effecting the closure of the circuit of the signal-receiving apparatus thereat. 55. A party line telephone system including a line circuit leading from a transmitting to a plurality of receiving stations, each having telephonic apparatus in a telephonically continuous but metallically discontinuous bridge between the sides of the line circuit, signal-receiving apparatus at the receiving stations included in independent circuits one set of normally restrained instrumentalities distributed among the receiving stations and, when released, performing their functions in succession, to close one of two breaks normally existing in the circuit of the signal-receiving apparatus at each receiving station, electro-magnets at the receiving stations in metallically continuous bridges between the sides of the party line, and switching mechanism at the transmitting station for operating said electro-magnets to release said set of instrumentalities and operating the second set of instrumentalities substantially simultaneously to cause one instrumentality of each set at a selected station jointly to take part in effecting the closure of the circuit of the signal-receiving apparatus thereat. 56. A party line telephone system including a line circuit leading from a transmitting to a plurality of receiving stations, each having telephonic apparatus in a telephonically continuous but metallically discontinuous bridge between the sides of the line circuit, signal-receiving apparatus at the receiving stations included in independent circuits, one set of normally restrained instrumentalities distributed among the receiving stations and, when released, performing their functions in succession, to close one of two breaks normally existing in the circuit of the signal-receiving apparatus at each receiving station, a second set of instrumentalities distributed among the receiving stations and having government exercised from the transmitting station that is independent of government exercised by the first set of instrumentalities, to close the second of the two breaks normally existing in the circuit of the signal-receiving apparatus at each receiving station, electro-magnets at the receiving stations in metallically continuous bridges between the sides of the party line, and switching mechanism at the transmitting station for operating said electro-magnets to release said set of instrumentalities and operating the second set of instrumentalities substantially simultaneously to cause one instrumentality of each set at a selected station jointly to take part in effecting the closure of the circuit of the signal-receiving apparatus thereat. 57. A party line telephone system including a line circuit leading from a transmitting to a plurality of receiving stations, each

having telephonic apparatus in a telephonically continuous but metallically discontinuous bridge between the sides of the line circuit, signal-receiving apparatus at the receiving stations included in independent circuits, one set of normally restrained instrumentalities distributed among the receiving stations and, when released, performing their functions in succession, to close one of two breaks normally existing in the circuit of the signal-receiving apparatus at each receiving station, a second set of instrumentalities distributed among the receiving stations and having government exercised from the transmitting station that is independent of government exercised by the first set of instrumentalities, to close the second of the two breaks normally existing in the circuit of the electro-magnetic responsive apparatus at each receiving station, electro-magnetic mechanism at the receiving stations for re-

leasing said set of instrumentalities and operating the second set of instrumentalities, electro-magnets at the receiving stations in metallically continuous bridges between the sides of the party line, and switching mechanism at the transmitting station for operating said electro-magnets to effect the substantially simultaneous operation of said electro-magnetic mechanism to cause one instrumentality of each set at a selected station jointly to take part in effecting the closure of the circuit of the signal-receiving apparatus thereat.

In witness whereof, we hereunto subscribe our names this 25th day of February A. D., 1909.

GEORGE C. CUMMINGS.
ARCHIBALD WRAY.
